UNITED STATES PATENT OFFICE.

AARON J. NELLIS, OF PITTSBURG, PENNSYLVANIA.

WIRE-FASTENING DEVICE FOR FENCE-POSTS.

SPECIFICATION forming part of Letters Patent No. 337,857, dated March 16, 1886.

Application filed June 27, 1885. Serial No. 170,034. (No model.)

To all whom it may concern:

Be it known that I, AARON J. NELLIS, a citizen of the United States, residing at Pittsburg, in the county of Allegheny and State of Pennsylvania, have invented certain new and useful Improvements in Wire-Fastening Devices for Fence-Posts; and I hereby declare the following to be a full, clear, and exact description of the same, reference being had to the accompanying drawings, in which—

Figure 1 is an elevation of a fence-post provided with a wire-holding device embodying my invention. Fig. 2 is a rear view of a portion of the post, showing the manner of securing the wire-holding device thereto. Fig. 3 is a detail sectional view of a post, showing the position of the device; Fig. 4, a perspective view of the device; and Fig. 5 is an enlarged rear view of a portion of the post, showing the slot for the reception of the wire-fastening device.

Like letters refer to like parts wherever they occur.

The object of the present invention is to provide a simple and effective means of securing the wire or ribbon to the post in such manner as will permit the ready insertion or removal of the wire or ribbon and at the same time so hold the wire or ribbon as to allow for expansion and contraction, while preventing accidental displacement of the wire.

I will now proceed to describe my invention, so that others skilled in the art to which it appertains may apply the same.

In the drawings, A indicates a metallic fence-post, which should have a web and projecting flanges, or, as is preferable, may be semicircular in cross section, and formed from open-hearth steel, cast-steel, or Bessemer steel, by guttering a bar thereof; or, if preferred, either angle or double T iron shapes may be used, as the desirable feature is to have a recess or depression into which the point of the hook may project.

B indicates the fastening-hook, which has an irregular curve of the general character shown, so as to form a swell, b, for the reception of the wire or ribbon, and a beak or

point, c. This hook is so pivoted on the post 50 that when it swings or drops down the wire C or ribbon D can be readily inserted; but when the wire or ribbon is moved or lifted the hook B moves with it, and the point or beak c is carried into the trough or recess a 55 of the post.

The hook B is made by doubling a wire to form two parallel arms, then bending the free ends e at right angles in opposite directions to form a T, and finally bending the parallel 60 arms into the irregularly-curved hook hereinbefore specified.

For securing such a hook to the post, the post is slotted at the bottom of gutter a, as at h, said slot being sufficiently large to allow the 65 hook to enter freely and to vibrate with the wire or ribbon.

As a hook of the character described has two spring-arms, said arms will bind on the edges of slot h and prevent the displacement 70 and loss of the hook when the fence wire or ribbon is displaced.

The advantages of my invention are, first, as the post does not require edge slots for the fence-wires it can be made of much lighter 75 material; second, the simplicity of the fastening and the manner of connecting it with the post reduces the labor and cost of manufacture; third, while the wire is so held that it can expand or contract without breaking 80 or displacing the post, it cannot be accidentally displaced; fourth, the wire or ribbon can be readily removed when it is desirable to do so for moving the fence or for other purposes.

Having thus set forth the nature, operation, and advantages of my invention, what I claim, and desire to secure by Letters Patent, is—

1. The combination, with a guttered post 90 of a hook having a wire swell, b, and beak c, said hook pivoted to swing within the gutter of the post, and adapted to hold a fence wire or ribbon, substantially as and for the purposes specified.

2. The combination, with a guttered post, having a hook-slot, h, of a wire hook having laterally-bent spring-arms forming a T-head

85

95

for securing the hook in the slot of the post, substantially as and for the purposes specified.

3. The fencing-wire hook composed of the doubled wire having the swell *b* and the laterally-projecting spring-arms, and *T*-head *e e*, substantially as and for the purposes specified.

In testimony whereof I affix my signature, in presence of two witnesses, this 28th day of May, 1885.

AARON J. NELLIS.
